UNITED STATES PATENT OFFICE.

HECTOR LEDOUX, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LAPPET-LOOM.

SPECIFICATION forming part of Letters Patent No. 733,490, dated July 14, 1903.

Application filed March 12, 1903. Serial No. 147,393. (No model.)

To all whom it may concern:

Be it known that I, HECTOR LEDOUX, a citizen of the United States, residing at Worcester, in the county of Worcester and State of Massachusetts, have invented certain new and useful Improvements in Lappet-Looms, of which the following is a specification.

My invention relates to a "lappet-loom," so termed, for weaving, by means of needles, figures or designs on the face of the fabric in the well-known way.

The object of my invention is to improve upon the construction of the needle-operating mechanism of a lappet-loom as ordinarily made, and more particularly to increase the range of movement and the variety of movement of the needle-bar carrying the needles transversely of the fabric.

In my improved construction I use two pattern-surfaces having elevations of varying heights and a lever for each pattern-surface, both levers connected with a single needle-bar having thereon the needles which carry the lappet-threads. The movement of either lever or both levers by the operation of the pattern-surfaces thereon will communicate a longitudinal movement to the needle-bar to place the needles carrying the lappet warp-threads in varying positions over the sheds of the usual warp-threads and interweave the lappet warp-threads on the surface of the fabric to produce the desired figures or designs in the usual manner in lappet-weaving. The two pattern-surfaces may be made up or formed of different elevations to produce any desired figure by the movement of the needle-bar, and one of the pattern-surfaces may be provided for several successive picks or movements of the pattern-surface with elevations of the same height, so that the lever of said pattern-surface will remain at rest and not be moved by said pattern-surface, while the other pattern-surface may have elevations of varying heights, so that the movement of the needle-bar will be governed only by the lever of said pattern-surface. When the two pattern-surfaces have elevations of varying heights, the two levers of said pattern-surfaces will act, through the connection to the needle-

bar, to communicate to the needle-bar a movement equal to the combined movements produced by each of said levers. In order to give an increased movement to the needle-bar over that produced by the movement of one of the levers, I make a part of the connection to the needle-bar, one end of which is attached to one of the levers, flexible, and extend it down, and pass it loosely around a pulley on the other lever and then carry it up to form a loop around said pulley before it passes to and is connected with the needle-bar. The movement of the pulley on the lever in the loop of the connection produces an increased movement of the needle-bar over the movement of the lever, as will be well understood.

My invention consists in certain novel features of construction of my improvements.

As my improvements are adapted to be applied to any of the well-known forms of jacquard or pattern-chain looms, I have only shown in the drawings detatched portions of a loom with my improvements thereon sufficient to enable those skilled in the art to understand the construction and operation thereof.

Referring to the drawings, Figure 1 is an end elevation of a loom-frame and lay with my improvements applied thereto. Fig. 2 is, on an enlarged scale, a perspective view of parts of my improvements shown in Fig. 1 detached; and Fig. 3 is, on an enlarged scale, a plan view of a portion of the loom-frame and lay and needle-bar and connections detached.

In the accompanying drawings, 1 is the loom-frame; 2, the lay-sword, pivotally supported at its lower end in the usual way.

3 is the lay; 4, the connector to the crank-shaft; 5, the crank-shaft, and 6 the bottom shaft. Said crank-shaft and bottom shaft are connected by gears (not shown) in the usual manner.

Supported on the lay and adapted to slide longitudinally in the guides 7 thereon is the needle-bar 8, carrying the lappet-thread needles, which are attached to clamps 9, by which the needles are secured to the needle-bar 8 in the usual way. To one end of the needle-bar 8 is attached a spring 10, (see Fig.

3,) which acts to move the needle-bar to its extreme right-hand position or to its normal position when not acted on by the mechanism connected to its other end.

5 The mechanism for raising and lowering the needle-bar is not shown and may be of any well-known construction and operation.

All of the above parts may be of any ordinary and well-known construction.

10 I will now describe my improvements.

A shaft 11 is mounted at its inner end in a bearing 12, secured to the loom-frame. (See Fig. 2.) Said shaft 11 has fast thereon a collar 11' and a ratchet-wheel 13, which is rotated by a pawl 14, in this instance connected with an eccentric 15 on the bottom shaft 6. The revolution of the bottom shaft 6 communicates, through the eccentric 15, motion to the pawl 14 to intermittently rotate the 20 ratchet-wheel 13. Also fast on the shaft 11 is a cam 16, forming in this instance the pattern-surface to operate the lever 17, which is pivoted at one end on a pin 18 in a stand 19, fast to the loom side. The lever 17 carries 25 in this instance a plate or surface 17', which extends in the path of and is engaged by the cam or pattern surface 16, and on the end of the lever 17 is pivotally mounted a pulley 21.

Upon the upper part of the loom-frame is 30 secured a stand 22, and in bearings on said stand is mounted a shaft 23, having fast thereon a hand-wheel 24 and a pattern-chain cylinder 25, carrying the pattern surface or chain 26, made up of links 26' of different elevations in the usual way. Rotary motion is 35 communicated to the shaft 23 in any well-known way from some driven part of the loom.

On the stand 22 is pivoted on a pin 27 one 40 end of the lever 28, carrying in this instance a roll 29, which extends over and rests upon the pattern chain or surface 26. To the end of the lever 28 is attached one end of a connection 30, which extends downwardly and 45 passes loosely around the pulley 21 on the lever 17 and from said pulley passes upwardly and over a guide-pulley 31 on a stud 32 on a stand 33, secured in this instance to the back side of the lay at the end thereof and 50 is connected by a wire or link 34 to the end of the needle-bar 8, as shown in Fig. 3.

The cam 16 and the pattern chain or surface 26 form in this instance the two pattern-surfaces hereinbefore referred to, and the lever 17 and the lever 28 are the two levers of 55 said pattern-surfaces.

The flexible connection 30 connects the lever 28 and also the lever 17 with the needle-bar 8 to move the needle-bar in one direction 60 longitudinally and with it the needle transversely of the fabric, and the spring 10, attached to the needle-bar 8, acts to draw it in the opposite direction and to hold the levers 17 and 28 in contact with their pattern-surfaces. 65

From the above description, in connection with the drawings, the operation of my im-

provements will be readily understood by those skilled in the art.

It will be seen that if the pattern-surface 70 26 has a number of pattern surfaces or elevations 26' thereon of the same height the revolution of said pattern-surface as long as the elevations remain of the same height will not move the lever 28. Consequently the connection 30 from said lever will not move the needle-bar; but the rotation of the second pattern surface or cam 16 will through its lever 17 move the needle-bar longitudinally, according to the shape of the cam 16, by reason 80 of the engagement of the pulley 21 with the connector 30, and, vice versa, if the shape of the cam 16 is such that the revolution of said cam will not move the lever 17 said lever will remain at rest and the needle-bar will be 85 moved longitudinally through the connection 30 by the lever 28, provided the pattern-surface 26 acting on said lever has elevations of varying heights. It will thus be seen that the longitudinal movement of the needle-bar may 90 be governed by the movement of the lever of one pattern-surface only. If both the pattern-surface 26 and the cam 16 have elevations thereon of varying heights, the two levers 17 and 28 will act, through the single connection 95 30 to the needle-bar, to communicate a longitudinal movement to said bar equal to the combined movements produced by each of the levers. In this way the movement of the needle-bar will be greatly increased over 100 the movement communicated to it by one of the pattern-surfaces, and, further, by reason of the connection 30 being loosely looped or passed around the pulley 21 a downward movement of the lever 17 and pulley 21 will 105 produce an increased movement of the connection 30 intermediate said pulley 21 and the needle-bar, and consequently an increased movement of the needle-bar. For example, a downward movement of the lever 17 of half 110 an inch will by reason of the loop in the connection 30 produce a downward movement of an inch on the connection, and consequently a movement of an inch on the needle-bar.

The advantages of my improvements will 115 be readily understood by those skilled in the art.

It will be understood that the details of construction of my improvements may be varied, if desired, and may be adapted to be 120 applied to any well-known form of loom for weaving lappet goods. Instead of the cam 16 a pattern-surface corresponding to the pattern-surface 26 or any other well-known style of pattern-surface may be used.

I preferably use two pattern-surfaces, as hereinbefore described; but, if desired, in weaving some patterns the pattern-surface 26 may be dispensed with and the end of the connection 30 attached in a fixed position or 130 to some stationary part, allowing the pulley 21 on the lever 17 to run loosely in the loop of the connection 31 to produce an increased motion of the needle-bar, as above described.

Having thus described my invention, what I claim as new, and desire to secure by Letters Patent, is—

1. In a lappet-loom, two rotary pattern-surfaces, provided with elevations of varying heights, two levers, one for each pattern-surface, a needle-bar, a connection intermediate said levers and said bar, to communicate to said bar a longitudinal movement equal to the combined movements produced by said levers, substantially as shown and described.

2. In a lappet-loom, two rotary pattern-surfaces, provided with elevations of varying heights, a lever for each pattern-surface, a needle-bar, a connection from said bar to both of said levers, said connection adapted to be moved by either, or both of said levers, to

give a longitudinal motion to the needle-bar, substantially as shown and described.

3. In a lappet-loom, two rotary pattern-surfaces, provided with elevations of varying heights, a lever for each pattern-surface, a pulley on one of said levers, a needle-bar, a connection from said bar to both of said levers, said connection loosely looped around said pulley on one of said levers, and adapted to be moved by either, or both of said levers, to give a longitudinal motion to the needle-bar, substantially as shown and described.

H. LEDOUX.
